LU J. COOLEY, OF LOS ANGELES, CALIFORNIA.

PUMP.

1,197,914.

Specification of Letters Patent. Patented Sept. 12, 1916.

Application filed March 4, 1915. Serial No. 12,104.

To all whom it may concern:

Be it known that I, LU J. COOLEY, a citizen of the United States, and a resident of Los Angeles, in the county of Los Angeles 5 and State of California, have made certain new and useful Improvements in Pumps, of which the following is a specification.

My invention is an improvement in pumps and has for its object to provide a pump 10 having means for raising the water and adapted to be operated by power or in any other suitable manner and having means in connection with the water raising means and operated by the operating means, for 15 aerating the water, that is, for thoroughly impregnating the water with air to assist in raising the water.

In the drawings: Figure 1 is a vertical section through the improved pump with 20 the operating mechanism in side elevation, Fig. 2 is a section on the line 2—2 of Fig. 1, with parts omitted showing the connection between the walking beam and the piston, Fig. 3 is an enlarged vertical section of 25 the compressor mechanism, Fig. 4 is a section on the line 4—4 of Fig. 3, Fig. 5 is an enlarged detailed section of the air discharging mechanism, Fig. 6 is an enlarged section 30 on the line 6—6 of Fig. 5, Fig. 7 is an enlarged section of the lower end of the beam, and Fig. 8 is a section on the line 8—8 of 35 Fig. 7.

In the present embodiment of the invention a pump is shown comprising a cylinder 40 consisting of telescoping sections, namely: an upper section 1 and a lower section 2 fitting within the upper section and connected therewith in any suitable manner and a T 3 is connected with the upper end of the upper section the T having a lateral outlet 4 to which a discharge pipe, indicated in dotted lines, may be connected for leading the water to the point of utilization. The upper end of the T is closed by a head 5 45 having a stuffing box 6 at the axis of the casing and a cap 7 is connected with the lower end of the inner or lower section of the casing, the cap having a perforate semispherical portion 8 and an annular rib or flange 9 at the junction of the perforate portion with the body of the cap. The upper end of the upper section 1 and the T have abutting flanges 10, which may be connected together in any suitable manner.

An air compressor cylinder 11 is arranged 55 above the casing 1—2 and coaxial therewith, the cylinder being supported by rods 12 connected at one end to the cylinder and at the other end to the well casing. A ring 13 of angle material is arranged intermediate 60 the ends of the cylinder, the ring having one portion fitting the cylinder and secured thereto in any suitable or desired manner and a portion extending perpendicular thereto to which the upper ends 65 of the rods are connected. The rods 12 are four in number being arranged at angular intervals of 90° and the lower ends of the rods are passed through the head 5 and through a flange 14 at the upper end of 70 the T and are secured to the head and flange in any suitable manner.

The upper end of the cylinder 11 is closed by a perforate head 15, the head being secured to the cylinder by means of a ring 16 75 of angle material. The ring has a portion fitting the cylinder and a portion extending at right angles thereto abutting the under face of the head. The lower end of the cylinder is closed as indicated at 17 and a stuffing box 18 is arranged at the center of the head and at the axis of the cylinder.

A foot valve is arranged at the bottom of the well casing in the section 2 and the said foot valve comprises a ring 19 fitting within a seat 20 within the cap 7 and a ring 21 has a threaded engagement with the ring 19 above the seat. The ring supports a central sleeve 22 above the same and at the axis of the ring by means of arms 23, said arms being integral at one end with the ring and at the other with the sleeve. Each arm is provided on its inner face with a guide rib 24 and a disk valve 25 is arranged between the arms, the valve having radial notches 26 90 for engaging the ribs to guide the valve in its rising and falling movement. The valve normally rests upon the upper end of the ring and it will be obvious that when the water is drawn upward through the ring the 95 said water will lift the valve and will flow past the same into the casing 1—2.

A plunger is provided for lifting the water, the plunger comprising a ring 27 externally reduced and threaded at its upper end, 105 and the said reduced portion is engaged by a ring 28. The ring 28 supports an internally threaded sleeve 29 above the ring 27

and at the axis of the casing 1-2 by means of arms 30, the arms being integral at one end with the ring and at the other with the sleeve. Each arm is provided on its inner 5 face with a guide rib 31 and a disk valve 32^a is arranged between the arms, the valve having radial notches similar to the notches 26 of the valve 25 for engaging the ribs to guide the valve in its rising and falling 10 movement. A piston rod 32 has a threaded engagement at its lower end with the sleeve 29 and the upper end of the rod is enlarged to form a head 33 which fits within the lower end of a hollow plunger rod 34 and is secured 15 thereto in any suitable or desired manner. The upper end of the hollow rod 34 extends through the stuffing box 18 into the compressor cylinder 11, and a piston or plunger is secured to the said rod in the 20 cylinder.

The piston or plunger comprises a substantially cylindrical body 35 having its lower end closed and provided with a central internally threaded opening 36 for engagement by the tubular rod 34. The upper end of the body is internally threaded and a disk 37 is threaded into the body. The closed lower end of the body has an annular series of ports or passages 38, and a ring 30 valve 39 is arranged within the body, the valve normally resting on the ports 38 for closing the same and the valve is normally pressed downward by coil springs 40, the said springs being arranged between the 35 valve and the disk 37. The ring valve is guided in its movement by vertical guide ribs 41 on the inner surface of the body 35 of the plunger, the said ribs being arranged at angular intervals of 90° with respect to 40 each other.

Near its lower end the compressor cylinder 11 is provided with four laterally extending nipples 42, the said nipples forming inlet ports for the cylinder. Each nipple 45 is internally threaded near its outer end to receive a threaded plug 43, and each plug has an annular series of openings 44 and a central opening for receiving the valve stem 45. A valve 46 is connected with 50 each stem on the inner side of the plug and a coil spring 47 encircles each stem between the outer end of the plug and a stop 48 adjustable along the stem.

It will be obvious that when the plunger 55 35-37 moves upward, air will be drawn into the lower end of the cylinder through the ports or passages 43 of the plug, the air rushing in and opening the valves 46. As the piston moves downward the air will enter the 60 hollow body of the piston, lifting the valve 39 and will pass into the bore of the hollow rod 34, the said bore communicating freely with the interior of the piston. The air will pass down through the hollow tube 34 and 65 will be delivered in the casing 1-2 below

the level of the water through the elbows 49. Each elbow has one arm threaded externally to engage an opening 50 in the wall of the hollow rod, and the other arm is internally threaded as indicated at 51 and the 70 said arm extends upwardly approximately parallel with the axis of the rod 34. A valve seat 52 is formed in each elbow at the junction of the arms and a ball valve 53 cooperates with each seat, normally resting 75 on the seat to permit the air to pass out of the rod and to prevent the water passing into the rod. Four of the elbows 49 are provided, the said elbows being in fact check valves for permitting the air to pass out 80 from the rods and for preventing the entrance of water or air to the rod. A cross head is connected with the rod 34 above the heads 5 of the casing 1-2, the said cross head 54 having a central opening 55 for 85 receiving the rod 34, and the cross head is secured to the rod. The cross head is also provided with openings 56 near its ends for engagement by oppositely arranged rods 12, and outside of the openings 56 each end 90 of the cross head has a head 57 connected to the rod by a reduced portion, as shown. A pair of standards or uprights 58 is arranged adjacent to the casing 1-2, the standards or uprights being supported by a base 59, 95 which has an opening through which the upper section 1 of the casing 1-2 passes. The casing is supported in fixed position with respect to the base by means of a sectional clamping member or ring 60 which 100 is clamped on the section 1 below the flange 10 and the clamping ring rests upon the upper face of the base. The standards or uprights 58 are connected by a cross beam 61 which is secured to the respective standards by bolts and nuts 62, and bearings 63 are arranged on the beam at the top of each standard.

A walking beam 64 is arranged between the standards, the beam having journal pins 110 65 which are journaled in the bearings 63. The beam is forked at one end and the arms 66 of the fork have links 67 pivoted thereto at one end of the link, the other end of each link being journaled on the reduced portion 11 of the cross head between the adjacent head 57 and the body of the cross head. The other end of the beam is connected to a crank arm 68 on a crank shaft 69 by means of the link 70, the link being pivoted at one 12 end to the outer end of the walking beam and at the other end to the crank arm. The crank shaft 69 is journaled in a supporting base 71 and a gear wheel 72 is secured to the shaft intermediate its ends and the gear 12 wheel meshes with a pinion 73 on another shaft 74 also journaled on the base 71. The shaft 74 has a crank arm 75, which is engaged by one end of a pitman 76, the other end being connected to a cross head (not 13

shown) which in turn is connected to the piston rod of a gasoline engine indicated at 77, in the usual manner.

It will be obvious that when the engine 5 77 is running the crank shaft 74 will be rotated and will in turn rotate the crank shaft 69, but at a lower rate of speed through the gear and pinion connection 72—73. As the crank shaft 69 rotates the 10 walking beam 64 will be vibrated and the plunger rod 32—34 will be reciprocated to reciprocate the plungers in the casing and in the compressor cylinder. When the plunger 27 moves downward the water above the 15 foot valve will lift the valve 32, and will pass through the plunger to the space in the casing 1—2 above the plunger.

When the plunger moves upward the water above the plunger will be lifted and 20 water will rush in from the well intake at 7 through the openings in the perforated portion of the head, and pass the foot valve to the space within the casing 1—2 to fill the partial vacuum created by the upward 25 movement of the plunger. As this operation is continued the water will finally reach the lateral outlet 4 and will be delivered to the place of utilization. At the same time that the pump is being operated the air comp- 30 pressor is being operated. When the piston 35 moves upward, air rushes in through ports or passages 43 of the plugs 42 to the lower end of the cylinder 11.

When the plunger or piston 35 moves 35 downward the air within the lower end of the cylinder cannot pass out by way of the valves 46 and said air will lift the ring valve 39 and will pass into the chambered body of the piston or plunger and into the hollow rod 34. This air in the hollow rod 40 34 will finally lift the valves 53 and will pass out into the water, thereby aerating the water. The perforated head 15 of the cylinder 11 is for the purpose of equalizing 45 the pressure on the plunger and to prevent any air compression or partial vacuum between the said head and the plunger. The particular connection between the rod 34 and the walking beam eliminates any tendency 50 to wobbling or side movement of the plunger rod. It will be understood that the air being under pressure also raises the water. The plunger rod conducts this air under pressure to the bottom of the well 55 delivering it at the point where it is needed.

I claim:

1. A pump comprising a casing, a foot valve in the casing, a valved plunger mounted to reciprocate in the casing, a cylinder 60 supported above the casing and coaxial with the casing, a chambered piston in the cylinder, a plunger rod connected with the plunger and having a head at its upper end, a hollow piston rod connected with the piston 65 at one end and communicating with the in-

terior thereof, the head of the plunger rod filling and closing the lower end of the hollow rod, said rod having outlet elbows at its lower end, said outlets delivering upward, a check valve in each outlet for preventing the return of fluid to the rod, said cylinder having inlet ports at its lower end, spring controlled inlet valves for permitting air to enter and for preventing the escape of air, the piston having ports at the 75 under side thereof, a ring valve normally closing the ports, springs arranged between the valve and the piston and normally holding the valve closed and adapted to yield to permit the air to enter the piston when 80 the piston moves downward, said cylinder having ports in its upper end, and means connected with the hollow rod for operating the same.

2. A pump comprising a casing and 85 adapted to be inserted in a source of water supply, a foot valve in the casing, a valved plunger in the casing, a cylinder supported above the casing and coaxial therewith, a plunger rod connecting the plunger with the 90 piston, the upper portion of the said rod being chambered longitudinally, a chambered piston within the cylinder and with which the rod is connected, said rod communicating with the interior of the piston, the cylinder having check controlled inlet valves at its lower end, and the piston having check controlled inlet valves at its under side for admitting air to the piston and to the rod when the piston moves downward, said rod 100 having check controlled outlets near its lower end, and means connected with the rod for reciprocating the same.

3. A pump comprising a casing adapted to be inserted in the source of water supply, said casing having a foot valve, and a valved plunger mounted to reciprocate in the casing, a cylinder held coaxial with the casing above the same, a hollow piston within the cylinder, said cylinder having 110 check controlled inlets at its lower end, and the piston having check controlled inlets at its under side, a hollow piston rod connected to the piston and communicating with the hollow thereof at its upper end 115 and connected with the plunger at its lower end and having check controlled outlets near its lower end, and means engaging the rod for reciprocating the plunger and the piston.

4. In combination with the pump for raising water and having a plunger and a plunger rod connected with the plunger, of an air compressor supported above the pump, said air compressor comprising a 125 cylinder having check controlled inlets at its lower end, a hollow piston within the cylinder, a tubular connection between the piston and the plunger of the pump and communicating with the interior of the pis- 130

ton, said piston having check controlled inlets at its under side, and the tubular rod having check controlled outlets near its lower end, and means for reciprocating the rod, the piston, and the plunger.

- 5 5. A pump comprising a casing adapted to be inserted in the source of water supply, and having a plunger mounted to reciprocate therein, and a plunger rod connected with the plunger, of an air compressor supported above the casing, a connection between the pump plunger and the air compressor for operating the same to compress air when the plunger is operated, 10 15 means for operating the plunger, said connection between the compressor and the plunger being chambered and having check controlled outlets below the level of the water for delivering air to the water.
- 20 6. In combination, a reciprocating pump for raising water, an air compressor, a connection between the pump and the compressor for operating the same when the pump is in operation, said connection being hollow for delivering the air compressed by the compressor to the water below the pump.
- 25 7. In combination, a pump having a reciprocating plunger for raising water, an air compressor having a reciprocating piston for compressing the air, a tubular connection between the plunger and the piston for receiving compressed air from the compressor and delivering it below the water level to aerate the water, and means con-

nected with the connection for reciprocating the said connection.

8. In a pump, the combination with the casing having a foot valve and a plunger mounted to reciprocate in the casing and provided with a plunger rod extending above the casing, a walking beam journaled intermediate its ends adjacent to the casing, means connected with one end of the beam for vibrating the same, and a connection between the other end and the rod, said connection comprising a cross head having a central opening for engagement by the rod, the rod being connected to the cross head, said cross head having guide bearings on opposite sides of the piston rod and fixed rods extending through the bearings, the ends of the walking beam adjacent to the plunger rod being forked, and a link connecting each arm with the adjacent end of the cross head.

9. In combination a reciprocating pump for raising water and adapted to be inserted in the well, a compressor supported above the pump at the top of the well, a connection between the pump and the compressor for operating them together, and hollow to conduct the air from the compressor to the pump.
